COMBINED VANITY CASE, CIGARETTE
CASE, AND LIGHTER

Alfred F. Reilly, North Attleboro, Mass., assignor
to Evans Case Company, a corporation of
Massachusetts

Application January 22, 1934, Serial No. 707,694

5 Claims. (Cl. 206—41.4)

The invention relates to a combined vanity and cigarette case, and with regard to its more specific features, to a combined vanity, cigarette case and lighter.

5 One object of the invention is to provide a highly desirable and convenient arrangement of cigarette case, lighter and vanity case in a single structure. Another object of the invention is to provide an easily manipulated article of the type indicated. Another object of the invention is to provide a structure capable of dispensing cigarettes and powder from separate compartments in a single receptacle. Another object of the invention is to provide a structure for a double use 10 article which can be embodied in commercial articles in large quantities with a minimum manufacturing cost. Another object of the invention is to provide an extremely durable article. Other objects will be in part obvious or in 15 part pointed out hereinafter.

The invention accordingly consists in the features of construction, combinations of elements, and arrangements of parts as will be exemplified in the structure to be hereinafter described, and 20 the scope of the application of which will be indicated in the following claims.

In the accompanying drawings, in which are shown certain of various possible embodiments of the mechanical features of this invention,

30 Figure 1 is a front elevation of a combined cigarette and vanity case and lighter;

Figure 2 is a cross-sectional view taken on the line 2—2 of Figure 1;

Figure 3 is a longitudinal sectional view of the 35 upper part of the article of Figure 1, the parts being illustrated on a somewhat enlarged scale, the plane of the section being indicated by the sectional line in Figure 2, and this view being taken looking in the direction of the arrows 3—3 of Figure 2;

Figure 4 is a view which may be described according to the description of Figure 3, the parts being viewed, however, in the direction of the arrows 4—4 of Figure 2;

45 Figure 5 is a cross-sectional view taken on the line 5—5 of Figure 1;

Figure 6 is a perspective view of the vanity compartment assembly, open;

Figure 7 is a bottom view of the dispenser 50 unit;

Figure 8 is a perspective view of a long cigarette case, open, with vanity case;

Figure 9 is a front elevation of another combination cigarette and vanity case, showing the 55 interior parts in dotted lines.

Similar reference characters refer to similar parts throughout the several views of the drawings.

Referring first to Figures 1 and 2, I provide a pair of struck shells 20 and 21 made of a metal which may be easily formed in a press or the like. The shell 20 is slightly longer than the shell 21 and has a top wall flange 22. Both shells 20 and 21 are preferably of generally rectangular form although the sides may be slightly curved as shown.

As best shown in Figure 1, I connect the shells 20 and 21 together at the bottom or side by means of a hinge 23 which may comprise the usual integral bent-over hinge portions, several on each shell, and connected by the usual hinge pin passing through them, and at any point along the bottom or side I omit one or more hinge portions and place on the hinge pin a spring 24, the opposite ends of which engage the insides of the shells 20 and 21 thus resiliently urging them into 20 open position, one relative to the other.

The shells 20 and 21 thus constitute a cigarette case for the reception of cigarettes in a vertical position, Figure 1, and the shell 21 may 25 be referred to as a cover.

Still referring to Figures 1 and 2, to one of the shells 20 or 21 (as shown to the shell 21 which constitutes the cover) I fasten a pair of spring latch members 25, 25 as by rivets 26, 26. Latch members 25 have finger engaging portions 27 extending through slots in the sides of the cover 21, and they also have detents 28, 28 adapted to engage detents 29, 29 formed in the back wall struck shell 20. Thus the cover 21 30 is held in closed position as shown in Figures 1 and 2, and may be opened by pressing inwardly the finger portions 27, 27.

I provide an integral sheet metal member which extends longitudinally of the article a distance equal to the difference between the length of the shells 20 and 21 and which, with the cover 21, when closed, makes a complete front wall to the article, and which comprises a front wall portion 31 and a top wall portion 32, complementary to the top wall flange 22. I further provide a fuel tank bottom wall 33 which forms the upper boundary of the cigarette case compartment. I further provide a well 34 for the reception and mounting of lighter mechanism 40 45 50 55 50 which will be described. I also provide an internally screw threaded orifice member 35.

The parts 31, 32, 33, 34 and 35 are desirably affixed to each other and connected to the back wall shell 20 by soldering or brazing operations;

the top wall portions 22 and 32 are cut away for the reception of the well 34 and the orifice member 35, and for the better union of these parts and to give rigidity to the article the well 34 and the orifice member 35 may have top flanges 36, 37, respectively, overlapping the top wall 22, 32. I may provide an extra inside reinforcing member 38, if desired.

The structure just described forms an enclosed space for the reception of liquid fuel, which may be absorbed in cotton or the like which is placed in this enclosed space, and thus the parts constitute a fuel receptacle firmly secured to the struck shell 20.

On the top wall 22, 32, and in the well 34 I mount lighter mechanism preferably of the type fully described in the copending application Serial No. 646,754 filed December 12, 1932 by Robert S. Blair. Reserving, therefore, the right to supplement this description with the fuller description contained in the aforesaid copending application of Robert S. Blair, I briefly describe this lighter mechanism, which is the preferred form of lighter mechanism constituting part of the present invention, as follows:

A wick tube 40 extends through the flange 36 of the well 34 and through the top wall portion 32 and 22 and is securely affixed in place. A wick 41 extends through the tube 40 and into the fuel receptacle. A snuffer member 42 of the shape shown is pivotally mounted on a pin 43 which extends between upwardly extending ears 44 desirably formed integral with the well 34. The snuffer member 42 has a cap 45 which normally covers the upper end of the wick 41 and seats on the wick tube 40.

A finger piece member 46, of the shape shown, is pivotally mounted on a pin 47 extending between the ears 44. The finger piece 46 is normally urged upwardly by means of a spring 48 and the pressure of the spring 48 is transmitted to the snuffer 42 to hold the snuffer cap 45 closed by means of a forwardly extending portion 49 engaging the under side of the snuffer member 42. There is a spring connection between the finger piece 46 and the snuffer member 42 constituting a spring 50 looped around the pin 43. There is a latch member 51 normally preventing the rising of the snuffer member 42 because a latch 52 of the member 51 engages the pin 47, the latch 51 being urged into latching position by a small spring 53. Depression of the finger piece 46 results, at first, in no substantial movement of the snuffer member 42; finally, however, the bottom of the finger piece 46 or a lug 54 provided thereon engages the latch 51 unlatching the portion 52, whereupon the snuffer 42 flies upwardly under the influence of the spring 50. At such time a multi-toothed pawl member 55 which engages a ratchet wheel 56, rotates said ratchet wheel and a sparking wheel 57 integrally attached thereto, thus projecting sparks from a piece of pyrophoric material 58 and throwing them upon the wick 41. The ratchet wheel 56 and the abrasive wheel 57 are mounted upon the pin 47, and the multi-toothed pawl 55 is urged into engagement with the ratchet wheel 56 by means of a spring 59.

I have provided a tube 60 for the retention of the pyrophoric material 58, which is urged into engagement with the abrasive wheel 57 by means of a plunger 61 spring-pressed upwardly by a spring 62 that is held in position and which may be adjusted by means of a screw closure member 63. The tube 60 extends through the bottom

wall member 33 and new pieces of pyrophoric material 58 may be inserted into the tube 60 from the inside of the cigarette case. This construction insures a straight tube providing a uniform pressure of the pyrophoric material 58, and the small parts comprising the pyrophoric metal 58, plunger 61, and spring 62 are less easily lost when replacing pyrophoric metal because they fall into the cigarette enclosure.

I provide a screw closure 65 for the fuel tank seating in the threaded member 35, and a split tubular member 66 to hold extra pieces of pyrophoric material and which seats in the screw 65 may be provided. By reason of the fact that the fuel receptacle can be filled from outside the cigarette case, the wetting of the inside of the cigarette case with consequent spoiling of cigarettes is avoided.

The struck shells 20 and 21 make a complete handful, so that a firm grip may be had upon the entire article with the hand, locating the thumb over and upon the finger piece 46 which may thus be readily depressed to actuate the lighter. It will be seen that the flame is well removed from any finger, and it will be further seen that the lighter mechanism provides no parts which project outwardly beyond the edge or side walls of the cigarette case and receptacle, and thus the article may be very conveniently carried in a small pocket of a hand bag or the like.

Referring again to Figures 1 and 2, I provide a vanity case in the cover shell 21. This vanity case is generally designated by the numeral 70 and is affixed to the lip of a circular hole in the shell 21. As better shown in Figure 2, I provide an inside bezel ring 71 with an outwardly extending upper flange portion 72 and an inwardly extending lower flange portion 73 from which extend a plurality of tabs 74. Interlocking with the bezel 71 is an outside cylindrical ring 75 having an inwardly extending flange 76 on the bottom. The top of the ring 75 engages the under side of the flange 72, and the tabs 74 are bent over to hold the parts together. The ring 75 has a plurality of nicks 77 extending outwardly and just below the flange 72.

In the walls of the bezel 71 are formed resilient detents 78 by making a U-shaped cut through the metal, the U standing vertically, Figure 2, and the detents 78 constituting the remaining metal and having pressed inwardly portions 79 constituting snaps. Two or more of the detents 78 may be provided.

The entire unit thus far described may be snapped in place in the hole in the cover 21 as the nicks 77 can be forced downwardly past the lip of the hole and then snap outwardly locking the vanity case parts to the cover 21. To form the bottom of a powder compartment a metal cup member 80 may be forced over the outer cylindrical member 75, which it fits with a press fit. This metal cup member 80 also constitutes a presser member to press the cigarettes in the cigarette case.

Affixed to the outwardly extending flange portion 72, that is hingedly connected to it, is a vanity case cover 81 which may be constructed like the cover described in my U. S. Letters Patent No. 1,869,983 granted August 2, 1932, and said cover 81 may contain a rouge compartment and a mirror as described in the patent. Inside the bezel 71 and held resiliently in position by the detents 78 is a powder dispensing member which is shown in section in Figure 2, in bottom plan 75

view in Figure 7, and which may be the same as the dispensing member shown and described in the aforesaid patent. This dispensing member comprises a dispensing cover 82 and a dispensing plate 83, as described in the patent, and it is here noted that when you press the plate 83 downwardly a gap is opened between it and the cover 82 for the dispensing of powder.

It will be seen that the article described allocates space for a lighter, a cigarette case and a vanity case so that the entire article is no larger than the usual cigarette case, and that the vanity case compartments may be reached without disturbing the cigarette compartment and vice versa, and in any position of the parts the lighter may be lit, and the casings constitute a handle for the lighter. The cover of the cigarette case provides a foundation frame for the vanity case and the back of the cigarette case provides a foundation frame for the lighter. The construction of the parts permits manufacturing methods which enable the article to be embodied in well operating units cheaply.

Referring now to Figure 8, I have shown a long flat cigarette case constituting a pair of similar struck shells 90 and 91 of which the shell 90 may be considered the cover. The shells 90 and 91 are connected by a hinge 92 of the type already described, and a spring 93 urges the shells apart. One end of the spring 93 reacts against a presser member 94 of the shape shown, and thus urges the presser member 94 into engagement with cigarettes in a cigarette compartment 95. The bottom wall of the cigarette compartment 95 constitutes a narrow strip of metal 96 suitably secured in place as by the use of solder. In the cover 90 is a pin 97 which engages with the lip of a latch detent 98 resiliently held in place by a long strip of metal 99 riveted at 100, 100 to the shell 91, and a finger piece 101 extends outwardly through a slot in the shell 91 and thereby the cigarette case can be opened.

In the cover 90 is a vanity case unit 102 which may be exactly as already described, and it is noted that the cover of the vanity case is arranged to open in the same direction that the cigarette case opens, that is to say the hinge for the vanity case cover, not shown, is parallel to the hinge 92.

Referring now to Figure 9, I have therein illustrated a combination vanity case and cigarette case comprising a vanity case 105 in the cover 106 of a cigarette case which has inside it a presser member 107 and which has a latch 108 similar to the latch 98 and associated parts already described. As in the case of the article of Figure 8, the vanity case preferably opens in the same angular direction as the cigarette case. The articles of Figures 8 and 9 have all the features and advantages already set forth in connection with the embodiment of Figures 1 to 7 inclusive other than those involving the lighter mechanism and its construction.

It will thus be seen that there has been provided by this invention an article in which the various objects hereinabove set forth, together with many thoroughly practical advantages, are successfully achieved. As many possible embodiments may be made of the above invention, and as many changes might be made in the embodiments above set forth, it is to be understood that

all matter hereinbefore set forth, or shown in the accompanying drawings, is to be interpreted as illustrative and not in a limiting sense.

I claim:

1. In an article of the class described, in combination, a container having an enclosure in the upper portion thereof, a cover plate hingedly connected to one edge of said container and extending therefrom to said enclosure, said cover plate having an aperture therein, a lighter mounted on one of the walls of said enclosure, and a receptacle mounted in said aperture in said cover plate and having a wall which forms a wall portion of the container when the cover plate is in closed position.

2. In an article of the class described, a pair of rectangular struck shells in the form of a container and cover respectively, hinge means connecting said shells, a receptacle in said container having a wall constituting one side of a cigarette compartment, a cup member fastened to said cover and extending toward said container but spaced from said cigarette compartment in all relative positions of said shells, said cup member constituting the body of a powder compartment and a wall portion of the container when the cover is in closed position.

3. In an article of the class described, in combination, a cigarette container, a cover for said cigarette container hingedly connected thereto, and a vanity case mounted in said cover including a cup-shaped portion depending from said cover and extending toward the bottom of said container and forming a wall portion of the container when the cover is in closed position to act as a presser member for cigarettes disposed within said container.

4. In an article of the class described, in combination, a container, an enclosure formed upon one end of said container, a lighter adapted to fit into said enclosure, said container being adapted to hold cigarettes, a cover member hingedly connected to said container, the upper edge of said cover member contacting the lower portion of said enclosure when in closed position, a vanity case depending from said cover member and extending towards said container and constituting a wall portion of the container when the cover member is in closed position, said vanity case being adapted to hold powder, and a lid for said vanity case, said lid being hingedly connected to said vanity case.

5. In an article of the class described, in combination, a container, an enclosure formed upon one end of said container, a lighter adapted to fit into said enclosure, said container being adapted to hold cigarettes, a cover member hingedly connected to said container, the upper edge of said cover member contacting the lower portion of said enclosure when in closed position, a cup-shaped member depending from said cover member and constituting a wall portion of the container when the cover member is in closed position, the bottom of said cup-shaped member being shaped to act as a presser member for cigarettes disposed within said container, and a lid for said cup-shaped member, said lid being hingedly connected to said cup-shaped member.
